Des. 219,575
Patented Dec. 29, 1970

219,575

COMBINED FOOD PACKAGING CUP AND COVER THEREFOR

David Douglas, 1332 S. 26th St.,
Manitowoc, Wis. 54220

Filed Oct. 10, 1969, Ser. No. 19,493

Term of patent 14 years

Int. Cl. D9—04

U.S. Cl. D9—220

Fig. 1

Fig. 3

Fig. 2

Fig. 4

FIG. 1 is a front elevational view of a combined food packaging cup and cover therefor, showing my design;

FIG. 2 is a rear elevational view;

FIG. 3 is a top plan view; and

FIG. 4 is a bottom plan view.

I claim:

The ornamental design for the combined food packaging cup and cover therefor, substantially as shown.
